METHOD OF AND APPARATUS FOR UNITING
BASES TO THE GLASS BULBS OF ELEC-
TRIC INCANDESCENT LAMPS AND SIMI-
LAR ARTICLES

Peter Herre, deceased, late of Berlin-Fichtenau, Kreis Niederbarnim, Germany, by Margarete Herre, nee Erpel, Gerda Herre, and Ursula Herre, heirs, Berlin-Fichtenau, Kreis Niederbarnim, Germany, and Arthur Hix, Berlin-Karlshorst, Germany, assignors to General Electric Company, a corporation of New York

Application December 14, 1933, Serial No. 702,430
In Germany December 17, 1932

11 Claims.

(Cl. 18—5)

The invention relates to methods of and apparatus for uniting bases to the glass bulbs of electric incandescent lamps and similar articles.

The usual method of cementing metal bases to the bulbs of electric lamps consists in applying an annular shoulder of cement to the inner edge of the base, then placing the base over the neck of the bulb with the cement in contact with the said bulb neck and heating to harden the cement, as shown in Patent No. 1,306,643 to Swan.

According to the invention, a base, usually comprising a threaded cylindrical metal shell, is placed on the neck of a glass bulb after which the correct amount of cement is inserted in the said base through an opening therein. The cement is then heated to harden it. The cement may be advantageously introduced through the usual hole in the end of the base through which a lead wire extends to the end contact. In this method, the cement flows into the space between the base shell and the bulb neck, thus insuring a uniform distribution of cement therebetween. In order to insure a compact and complete filling of this space a jet of compressed air may be introduced into the base through the said hole. In the old method described above there is a possibility of the displacement of the cement during the transferring of the base with the cement therein to the bulb neck.

Further features and advantages of the invention will appear from the following description of species thereof and from the drawings.

In the drawings, Fig. 1 is an elevation of apparatus comprising the invention; Fig. 2 is an elevation thereof in section and to a larger scale; Fig. 3 is a partially diagrammatic elevation of electrical contact mechanism which renders the cement applying mechanism non-operative when a lamp holder comes into position without a base; Fig. 4 is an elevation showing a compressed air nozzle in operative position; and Fig. 5 is an elevation of a milling attachment for cleaning the surface of the end contact of the base.

Referring to Fig. 1, a rotatable indexing table 10 is provided with a plurality of vertically reciprocating lamp holders 11 which consist of tubes connected to a vacuum source (not shown) and have seats 12 at the upper ends thereof which support and firmly grip the bulbs 13 of electric incandescent lamps. The said lamp bulbs 13 have filaments 14 sealed therein (Fig. 2) and leading-in wires 15, 16 extending through said bulbs. A base comprising a screw threaded cylindrical metal shell 17 is placed over the neck of the bulb 13 so that one edge thereof rests on

said bulb. The opposite end of said base shell 17 is provided with an insulating mass 18 having an eyelet 19 sealed in the end thereof through which the lead wire 16 extends. The other lead wire 15 is bent down between the edge of the shell 17 and bulb 13. The lamp is maintained in an exact vertical position by an angular support 20 mounted on table 10 and extending upward adjacent to the holding tube 11 and having a horizontal portion 21 with a hole 22 therein which engages the upper end of the lamp base.

A cement container comprising a cylindrical metal tank 23 is disposed above the table 10 and axially of the lamp 13 and holder 11. The said container 23 is provided with a screw cover 24, an opening 25 in the side for filling it with cement 26, a cover 27 therefor, and a conically converging bottom 28. A nozzle 29 is mounted in a spout 30 at the bottom, being held therein by a nut 31. A tube 32 is arranged in the axis of the container 23 so that it can reciprocate through the cover 24 and is closed at its lower end by a plug 33 which acts as a piston. A rod 34 is slidably mounted in the tube 32 and carries a needle 35 at its lower end. The plug 33 is provided with an axial hole 36 through which the needle 35 passes toward the hole in nozzle 29 when the rod 34 is moved downward. In order to prevent the tube 32 from carrying some of the cement 26 upward and to minimize agitation of the cement, a sleeve 37, which acts also as a guide for the said tube 32, is mounted on the cover 24. A cylindrical tube 38 is mounted on the lower end of the sleeve 37 and extends into the cement, thereby forming an air cushion or buffer in the space 39 which exerts a downward pressure on the cement when the tube 32 is raised.

The container 23 is mounted on a pair of arms 40 of a slide 41 which is slidably mounted in a vertical guide member 42 which is mounted on a stationary table 43 (Fig. 1). A vertical rod 44 is slidably mounted in the arms 40 and carries a cross-arm 45 at its upper end which is held in place by a nut 46. The cross-arm 45 terminates in a yoke 47 carrying pins 48 which engage an annular slot 49 in a collar 50 mounted on the tube 32. The tubular piston 32—33 is thereby suspended from the cross-arm 45 so that it can rotate. The upper end of the rod 34, which slides in the piston tube 32, carries a pin 51 which is engaged by the forked end 52 of a lever 53 which is pivotally mounted on a pin 54 in a support arm 55. The opposite end of the said lever 53 is connected by a link 56 to the cross-arm 45 and thus also to the vertically reciprocating rod 44. The

lower end of said rod 44 is connected by a link 57 to one end of a lever 58, the opposite end of which is pivotally mounted on a pin 59 in the table 43. The end of lever 58 is pulled down by a spring 60 which tends to keep a roller 61 on said lever in contact with a disc cam 62. The said cam 62 is mounted on a machine shaft 63 which completes one rotation for each indexing of the base cementing machine table 10. The piston 32-33 and rod 44 are moved up and down once during each rotation of the cam 62.

During the upward motion of the rod 44, the lever 58 is pivoted by the link 56 which also moves upward, so that the rod 34 and needle 35 are moved downward by the fork 52 acting on pin 51. The said needle 35 enters the nozzle 29 when the piston 32-33 is raised, thereby forcing the cement remaining in the said nozzle into the lamp base 17, and thus cleaning out said nozzle. Toward the end of the upward movement of the rod 44 and piston 32-33, a collar 64 on said rod 44 comes in contact with the upper arm 40 of slide 41 and lifts the slide together with the cement container 23 and the rod 34. The nozzle 29 is thus lifted clear of the lamp base 17 so the lamp is indexed to the next operating position and a new lamp is brought in position under said nozzle. The rod 44 is then moved downward and in the first part of the movement the slide 41 and container 23 follow along by the action of their weight until a stop screw 65 on the slide engages the top of the guide member 42. The nozzle 29 has then entered the hole in the eyelet 19 of the base 17 as shown in Fig. 2. The piston 32-33 then moves downward along with the rod 44. The said piston enters the spout 30 and forces cement through the nozzle 29 into the inside of the base 17, the cement being shown at 65'. During the downward motion of the piston 32-33, the lever 58 is pivoted counter-clockwise by the link 56 thus withdrawing the needle 35 from the nozzle 29 as shown in Fig. 2.

In order to prevent cement from being forced out when there is no base or lamp in the cement filling position, a contact mechanism shown in Fig. 3 is provided ahead of that position. The said mechanism comprises a vertical spring actuated plunger 66 mounted above the path of travel of the lamps so that it can reciprocate in stationary rail 67. A contact pin 68 on the upper end of the plunger 66 coacts with a counter-contact 69 mounted in a support 70 on rail 67. Both contacts are connected in a circuit 71 which includes a source of current 72 and the winding of an electromagnet 73. The core 74 of the electromagnet serves as a blocking pin for the lever 58 (Fig. 1) which is guided by cam 62. The core pin 74 is normally forced outward by a spring 75 so that it lies across the path of lever 58 and below it. If the tubular lamp holder 11 is provided with a lamp and base then, during the indexing motion into the cementing position, the top of the base 17 raises the plunger 66 so that the contact pin 68 engages pin 69. This closes the circuit 71, thereby energizing the electromagnet so that the core 74 is pulled in and lever 58 is released. While this has taken place, the face of cam 62 has receded from the roller 61 so that the lever 58 is immediately pulled down in front of the core pin 74 by spring 60, so that said pin 74 cannot again block the said lever 58 when the base 17 has passed the plunger 66. Then in the cementing position the piston 32-33 is moved downward by lever 58, link 57 and rod 44 to inject

cement into the base. While the lamp is still in the cementing position, the rod 44 and piston 32-33 move upward again when the lever 58 is raised. At the end of the upward motion the core 74 is again released and pushed out by spring 75 to assume a blocking position under the said lever 58. If the next holder 11 is not provided with a lamp and base, the plunger 66 will not be actuated and the lever 58 will remain up, thus holding the entire cementing mechanism at rest.

A compressed air nozzle 75 (Fig. 4) may be provided at the next operating position above the lamp 13 to direct a jet of air through the eyelet 19 and distribute the cement 65' compactly and uniformly in the space between the base shell 17 and the neck of the bulb 13.

The lamps then pass through the usual heating position to harden the cement and through the lead wire trimming mechanism where the ends of the lead wires 15-16 are cut off. In a subsequent operating position a milling tool 76 (Fig. 5) may be provided above the path of travel of the lamps and axially positioned thereto. The said milling tool 76 is fastened to the lower end of a vertical shaft 77 which reciprocates and rotates in a bushing 78 mounted on stationary portion 19 of the machine. A long-faced gear 80 is mounted on the shaft 77 above the milling tool 76 and meshes with a driving gear 81 which is mounted on a shaft 82 which is mounted in the stationary member 19. A collar 83 having an annular slot 84 therein is mounted on the upper end of shaft 77. Rollers 85 engaging the slot 84 are mounted in the yoke end 86 of a lever 87 which is pivotally mounted on a pin 88 in a support arm 89. The lever 87 comprises an angular downwardly bent portion 90 which carries a roller 91 at its end. The said roller 91 is kept in contact with a vertically reciprocating plunger 92 having an indentation 93 therein, by a spring 94.

When a lamp arrives in the operating position under the milling tool 76, the plunger 92 drops downward, the lever arm 90 is swung outward by spring 94 and the forward end of lever arm 87 is pressed downward. This causes the tool 76 to engage the surface of the eyelet 19 on base 17, and the rotating tool frees the said eyelet of cement which may have been deposited and hardened thereon. In subsequent operating positions the trimmed lead wires are soldered to the base shell 17 and eyelet 19 respectively. The milling operation leaves a clean surface on the eyelet 19 for soldering the lead wire 16 thereto. A compressed air nozzle 95 may be provided adjacent to the eyelet 19 to blow off the particles of cement and of the eyelet removed by the tool 76. The said nozzle 95 is fastened to the lever 87 by clips 96 and is connected by a hose 97 to a compressed air source.

A swinging brush 98 (Fig. 1) may be provided to clean the outside of the nozzle 29. Said brush 98 is mounted on a horizontal arm 99 which is mounted on a sleeve 100. Said sleeve 100 is rotatably mounted on rod 44 and has an annular groove 101 at the lower end which is engaged by a yoke arm 102. The sleeve 100 has a curved slot 103 therein which engages with a screw 104 mounted on the rod 44 so that when the said rod 44 is moved up and down, the screw 104, running in the slot, causes the sleeve 100 and brush 98 to swing horizontally back and forth, the brush thereby moving across the face of the nozzle 29. 75

What is claimed as new and desired to secure by Letters Patent of the United States is:

1. The method of uniting a base to the bulb of an incandescent electric lamp or similar article which consists in placing the said base over the neck portion of said bulb and injecting cement into said base through an opening therein to fill at least a portion of the space between said base and bulb neck.
2. The method of uniting a base comprising a screw threaded cylindrical metal shell having an eyelet at the end thereof to the bulb of an incandescent electric lamp or similar article which consists in placing the said base over the neck portion of said bulb and injecting cement into said base through the opening in said eyelet to fill at least a portion of the space between said base and bulb neck.
3. The method of uniting a base to the bulb of an incandescent electric lamp or similar article which consists in placing the said base over the neck portion of said bulb and injecting cement into said base through an opening therein to fill at least a portion of the space between said base and bulb neck, then directing a jet of compressed air into said base through said opening to uniformly distribute said cement therein.
4. A device for uniting bases to the bulbs of electric incandescent lamps and similar articles comprising a holder for holding a bulb in a neck-up position with a base on said neck portion of said bulb having an opening therein, a container for cement having a nozzle therein, means for causing a relative movement between said lamp holder and said container to cause said nozzle to penetrate into said base through said opening and means in said container for discharging cement through said nozzle into said base.
5. A device for uniting bases to the bulbs of electric incandescent lamps and similar articles comprising a container for cement having a nozzle therein, a tubular piston in said container, means for reciprocating said piston, a rod having a needle at the end thereof disposed inside of said piston and arranged axially of the said nozzle, and means for reciprocating said rod and needle independently of said piston to cause them to move downward when said piston moves upward so that said needle passes through said nozzle.
6. A device for uniting bases to the bulbs of electric incandescent lamps and similar articles comprising a container for cement having a nozzle therein, a tubular piston in said container, a rod having a needle at the end thereof disposed inside of said piston and arranged axially of said nozzle, a reciprocating rod disposed outside of said container parallel to said piston, a cross arm connecting said rod and piston, a slide connected rigidly to said container, a collar on said rod, means for raising said rod and causing said collar to engage said slide to lift said container, a lever pivotally mounted on a portion of said slide and engaging the upper portion of the said rod and pin at one end and a link connecting the other end of said lever to said reciprocating rod.
7. A device for uniting bases to the bulbs of electric incandescent lamps or similar articles comprising a substantially vertically disposed container for cement having a nozzle at the bottom thereof, a substantially vertical guide sleeve mounted in the upper part of said container, a reciprocating piston slidably mounted in said guide sleeve and adapted to force cement through said nozzle, and a tube secured to the lower end of said sleeve and surrounding a portion of said piston below said sleeve but spaced therefrom, said tube extending into said cement to form an air cushion around said piston between the surface of said cement and the lower end of said sleeve.
8. A device for uniting bases to the bulbs of electric incandescent lamps and similar articles comprising a container for cement having a nozzle therein, a brush disposed in juxtaposition with said nozzle and means for moving said brush across the face of said nozzle.
9. A device for uniting bases to the bulbs of electric incandescent lamps and similar articles comprising a movable table, a lamp holder in said table for holding a lamp bulb and base with the base uppermost, cement injecting mechanism disposed adjacent to the path of travel of said lamp and electrical contact mechanism disposed adjacent to the path of travel of said lamp ahead of said cement injecting mechanism comprising a resiliently mounted plunger disposed in the path of travel of said lamp base, and mechanism comprising an electrical circuit actuated by said plunger for rendering said cement injecting mechanism inoperative when a lamp holder which is devoid of a base passes by said plunger.
10. A device for uniting bases to the bulbs of electric incandescent lamps and similar articles comprising a movable table, a lamp holder in said table for holding a lamp bulb and a base on said bulb having an opening therein, cement injecting mechanism disposed adjacent to the path of travel of said lamp for injecting cement into said base through said opening, and a compressed air nozzle disposed in the path of travel of said lamp at a position subsequent to the cement injecting position, said nozzle being aligned with the opening in the said base, and means for injecting a jet of air through said nozzle into said base through the said opening.
11. A device for uniting bases to the bulbs of electric incandescent lamps and similar articles comprising a movable table, a lamp holder in said table for holding a lamp bulb and a base on said bulb having an opening therein, cement injecting mechanism disposed adjacent to the path of travel of said lamp for injecting cement into said base through said opening, and a cleaning device disposed adjacent the path of travel of said lamp at a position subsequent to the cement injecting position, and mechanism for causing said cleaning device to engage the outer portion of said lamp base around said opening and remove extraneous cement which may have been deposited thereon.
